[57] **CLAIM**

[**] Term: 14 Years

The ornamental design for a drill base for detachably securing to various size pipes, as shown and described.

[21] Appl. No.: 756,754

DESCRIPTION

[22] Filed: Sep. 9, 1991

FIG. 1 is a top, front and right side perspective view of a drill base for detachably securing to various size pipes showing our new design;

[52] U.S. Cl. D15/140
[58] Field of Search D15/139, 140, 141, 142,
D15/199; 408/16, 75, 76, 92, 100, 111, 712

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof; and,

FIG. 7 is a rear elevational view thereof.

Portions of the chain loop have been eliminated in FIG. 1 for ease of illustration, while the threaded tightenener and chain loop have been eliminated in FIGS. 2-7 for ease of illustration.
